(57) **CLAIM**

The ornamental design for a mirrored cabinet and dispenser of personal effects, as shown and described.

DESCRIPTION

FIG. 1 is a top, front, and left side perspective view of a mirrored cabinet and dispenser of personal effects showing my new design, in an opened position;

FIG. 2 is a top plan view thereof;

FIG. 3 is a front elevational view thereof;

FIG. 4 is a right side elevational view thereof;

FIG. 5 is a front elevational view thereof, in an opened position;

FIG. 6 is a right side elevational view thereof, in an opened position;

FIG. 7 is a top plan view thereof, in an opened position; and,

FIG. 8 is a top, front, and left side perspective view, in an open position, with the broken-line disclosure of a mirror on which it is mounted being shown for illustrative purposes only and forming no part of the claimed design.
